UNITED STATES PATENT OFFICE

2,311,921

FLASHER SWITCH

Charles Adler, Jr., Baltimore, Md.

Application August 8, 1941, Serial No. 406,037

3 Claims. (Cl. 200—81)

The present invention relates to relays of the flasher type and operating means therefor. The invention is particularly useful for operating a flashing type of airplane tail lamp as described in my Patent 2,265,095, dated December 2, 1941.

The principal object of the invention is to provide a simple and reliable means for operating a relay without recourse to either electro-magnetic means which frequently interfere with radio transmission and reception now a necessary part of most air craft or to thermal means which are affected by temperature changes to cause variation of the timing sequence.

A further object of the invention is to provide a construction which can be located in a part of the airplane remote from the location of the tail light or other light and which can be operated from the airplane motor or a separate prime mover or by means of a Venturi aspirating or suction system disposed in the slip stream of the propeller.

Another object of the invention is to provide a construction which is appropriately positioned to be operative regardless of the position of the airplane so that the plane may be maneuvered at will without danger of disrupting the relay for controlling periodic flashing of the tail light or other illuminating means.

The construction illustrated may be modified in various ways and it is to be understood that while I have illustrated the preferred forms of the invention, the use of gas operated means for controlling the relay may be carried out, using other types of operating structures.

Referring to the drawing:

Figure 1 is a diagrammatic view of one form of the invention;

Figure 2 is a diagrammatic view of the same form of the invention in which instead of relying on a Venturi-aspirator or suction means for reducing the pressure in the sealed chamber in which the parts are located, a suitable vacuum pump is interposed in the line to accomplish the result and operated from the motor of the plane or independently by a separate prime mover;

Figure 3 is a modification showing the manner in which a plurality of contact members may be operated to open and close electrical circuits for predetermined time intervals, and

Figure 4 is a detail plan view of Figure 3, with parts in section.

Referring to Figure 1, the casing 10 contains the electrical contact members 11 and the operating means therefor which is indicated as a whole at 12. This operating means includes a suitable rotor 13 mounted for rotation on a shaft 14 and having on its periphery a suitable number of vanes 15. A gear 16 is carried by the shaft 14 and engages a large gear 17 mounted for rotation on a shaft 18. This shaft 18 carries a

worm 19 which engages a large worm gear 20 carried on the shaft 21 and which shaft, in turn, carries a worm 22 for engaging the large gear 23 which is mounted for rotation on a shaft 25. Fixed to the shaft 25 is an insulating disc 26 having an insulated cam 27. The peripheral dimensions of the cam 27 and of the uncammed portion of disc 26 are substantially equal but may be varied as desired. Three spring contact members are employed in the construction shown in Figure 1 which are respectively numbered 30, 31, and 32. The flexible spring contact finger 31 leads through an insulating block 34 sealed in the housing and is connected by a wire 35 which leads through the switch 36 and battery 37 to the common wire 38. The contact fingers 30 and 32 are similarly supported in the sealed insulating block 34 and are connected by the wires 39 and 40 respectively to a pair of lamps 41 and 42. In order to rotate the rotor 13, a jet tube 43 is supported in the housing 10 so that its larger end 44 is open to the atmosphere while its smaller end 45 is projected in the path of rotation of the vanes on the periphery of the rotor 13. Preferably at the bottom of the casing, although it may be located in the sides or top, is a pipe 46 which in the construction shown in Figure 1, communicates with the smaller end 47 of a Venturi device 48. This Venturi structure 47—48 is disposed in the slip stream of the propeller and the reduced end 47 of the venturi has a vent 49 whereby in the travel of the plane, air will rush at high velocity through said vent and since the end of the pipe 46 is positioned at this point of high velocity and low pressure, the chamber 10 will be continuously evacuated by the suction created in much the same manner as a vacuum pump or aspirating device. The pressure in the chamber 10 is continuously being reduced to such an extent that air is being drawn through the jet 43 continuously and impinges upon the vanes of the rotor 13 at a pressure whereby the same is caused to rotate at a high speed which may be 9,000 R. P. M. The rotation of the rotor will, because of the mechanism heretofore described, cause the gear 23 to rotate and with it the shaft 25 and the cam 27. During one period of rotation of the shaft 25, the cam 27 will engage the contact finger 31 to move the same into contact with the finger 30 to thereby illuminate the lamp 41 which, for instance, may give a white beam and when the cam 27 is disengaged from the contact finger 31, it normally moves into contact with the contact finger 32 whereby the lamp 42 is illuminated and this may give a green or red beam. The peripheral length of the cam 27 may be so regulated that the interval of time that the lamps are respectively flashed is readily controllable; usually the peripheral length of the cam

27 is equal to about one-half the peripheral dimension of the disc 26 so that the lamps will remain illuminated for substantially equal periods of time.

The results just described are obtained by the use of the reduction gearing heretofore referred to so that while the rotor 13 revolves at a very high speed, the disc 26 and cam 27 will be revolved at a substantially lesser speed and this can be readily controlled by varying the transmission gearing and the peripheral dimensions of the cam and disc. In other words, the transmission reduction gearing is constructed and arranged to cause the lamps 41 and 42 to be alternately or intermittently lit for a predetermined interval as determined by the length of the cam 27 and makes allowance for variations in the speed condition of the plane as well as wind velocity. Thus variable means are provided to insure a uniform rate of flashing and not a continuous illumination of the lamps which might take place if the disc 26 were allowed to rotate at a high speed.

The pipe 46 is preferably positioned to communicate the suction means with the interior of the housing 10 on the side opposite the jet tube 43 and adjacent the rotor 14, so that the air upon impinging on the vanes of the rotor, is immediately withdrawn from the housing and is not allowed to circulate therein, since, if it were, the air and foreign matter entrained therewith might interfere with the operation of the transmission gearing and its associated parts.

It will be observed that the operation of the relay is wholly conducted without the inclusion of electromagnetic means which have been found to produce an inductive effect frequently objectionable in that it impairs radio transmission and reception. Also, this invention eliminates the variables occasioned by the effect of temperature changes on relays having thermal means.

Referring to Figure 2, instead of having a Venturi-aspirator construction, a vacuum pump 50 is connected to the line 46 and this vacuum pump may be operated from the airplane engine or a separate motor, not shown, to continuously maintain the required reduced pressure in the chamber 10.

Referring to Figure 3, I have illustrated a construction which will be useful where more than two lamps are to be flashed. In this construction, the shaft 25 is extended in the form of a cam shaft 51. The spring contact fingers 30', 32' and 52 are suitably supported in the insulated block 34' and when engaged by one of the cams 53, 54 or 55, will be moved into contact with one of the contacts 56 carried by the plate 57 respectively so that contact will be made to one of the lamps for a proper time interval consecutively. The common wire 38 is connected through the battery 37 and switch 36 by a wire 35 to the plate 57 and the spring contact fingers 30', 32' and 52 are connected by wires 58, 59 and 60 respectively to the lamps 61, 62 and 63 which are to be illuminated. The lamps may be colored red, green and white or clear.

It will be understood that the fluid pressure operated rotor may take a variety of forms as may also the jet pipe 43 and the exhausting apparatus, the particular requirement being, however, that a lightweight reliable construction be provided having a relatively few parts in which conventional electric relay mechanisms, such as electromagnetic means or thermal means are eliminated.

I claim:

1. An apparatus for aircraft comprising a housing, a rotor having vanes mounted in said housing, a jet tube extending into the housing, said tube communicating at one end with the atmosphere and having its other end disposed to direct a stream of air upon the vanes of said rotor to rotate the same at high speed when the aircraft is in flight, electrical contact members connected to electrical circuits to open and close the same, cam means in said housing for controlling the operation of said contact members, reduced transmission gearing operatively connected to said rotor and said cam means for operating the electrical contact members upon rotation of the rotor alternately to open and close said electrical circuits, and means for maintaining a reduced pressure in said housing, said last mentioned means being positioned relative to the jet tube to immediately withdraw the air after it impinges on the vanes of the rotor so that the air entering the housing does not interfere with the operation of the other parts therein.
2. An apparatus for aircraft comprising a housing, a rotor having vanes mounted in said housing, a jet tube extending into the housing, said tube communicating at one end with the atmosphere and having its other end disposed to direct a stream of air upon the vanes of said rotor to rotate the same at high speed when the aircraft is in flight, electrical contact members connected to electrical circuits to open and close the same, cam means in said housing for controlling the operation of said contact members, reduced transmission gearing operatively connected to said rotor and said cam means for operating the electrical contact members upon rotation of the rotor alternately to open and close said electrical circuits, and suction means communicating with the housing on the sides opposite to said jet tube for maintaining a reduced pressure in the housing for withdrawing the air after it impinges on the vanes of the rotor so that the air entering the housing does not interfere with the operation of the other parts therein.
3. An apparatus for aircraft comprising a housing, a rotor having vanes mounted in said housing, a jet tube extending into the housing, said tube communicating at one end with the atmosphere and having its other end disposed to direct a stream of air upon the vanes of said rotor to rotate the same at high speed when the aircraft is in flight, electrical contact members connected to electrical circuits to open and close the same, cam means in said housing for controlling the operation of said contact members, reduced transmission gearing operatively connected to said rotor and said cam means for operating the electrical contact members upon rotation of the rotor alternately to open and close said electrical circuits, a venturi having its smaller end extending in the direction of travel of the aircraft, said venturi having a vent in the smaller end thereof, and a pipe communicating the vent end of said venturi with said housing adjacent the rotor so that the air passing through said vent at high velocity continuously sucks air from the housing to reduce the pressure therein and causes the air to be drawn through the jet tube and impinge on the vanes with a force sufficient to rotate the rotor without circulating in the housing or interfering with the operation of the other parts in the housing.

CHARLES ADLER, JR.
